COLLAPSIBLE REVOLVING DOOR

Burns H. Uhrich, Independence, Kans., assignor
to The Atchison Revolving Door Co., Inde-
pendence, Kans., a corporation of Delaware

Application February 28, 1934, Serial No. 713,384

18 Claims. (Cl. 20—18)

This invention relates to revolving doors and has particular relation to revolving doors of the fully collapsible panic-proof type in which the wings of the door, although normally held in radial position, may be collapsed so as to be disposed in parallel relation on one side of the central support of the door.

It is an object of this invention to provide an improved door of the above type which will present a pleasing and attractive appearance, which will operate smoothly and efficiently and in which the several door wings are releasably held in radial position without resorting to the use of cable locks or brace arms between the wings.

It is a further object of this invention to provide a spring-pressed retaining mechanism for revolving doors to hold the wings in radial position while in normal operation, which has conveniently located means for manually controlling the tension upon the springs, and also automatically operable means for increasing the tension upon the springs when the wings are in radial position and for decreasing the tension when the wings are in collapsed, or partially collapsed, position.

Other objects will in part be obvious and will in part appear hereinafter.

For a fuller understanding of the invention, reference should be had to the accompanying drawings, in which

Figure 1 is a perspective view of a revolving door structure embodying features of the present invention;

Figure 2 is a plan view showing the upper surface of one of the wing supporting elements and a cross section of the four door wings in radial position;

Figure 3 is a plan view of a wing supporting element showing in full lines the grooves on the upper surface of the element, and in dotted lines, the grooves on the lower surface of the element;

Figure 4 is a sectional view taken in the direction of the arrows along the line 4—4 of Figure 3;

Figure 5 is a plan view similar to Figure 2 with the door wings in fully collapsed position;

Figure 6 is a detail view in cross section taken along the line 6—6, in the direction of the arrows, of Figure 5;

Figure 7 is a front elevation of one of the door wings, partially broken away, and with some of the intermediate portions omitted, showing in detail the novel retaining mechanism for releasably holding the door wings in radial position;

Figure 8 is a cross section taken in the direc-

tion of the arrows along the line 8—8 of Figure 7; and

Figure 9 is a sectional view taken in the direction of the arrows along the line 9—9 of Figure 7.

The revolving door illustrated in the drawings includes a central spindle 1, suitably journaled at its upper and lower ends in the ceiling and floor, and having two similar wing supporting disks 3 secured thereto at a short distance from the upper and lower ends respectively. Four door wings, designated by the numeral 4, are supported by the disks 3 so as to be normally held in radial position so that the four door wings, the disks 3 and the spindle may all rotate together, but a suitable connection is provided between each door wing and the disks so that under abnormal pressure, as in a panic, all of the wings will collapse into parallel relation on one side of the central spindle 1. The wing supporting disks 3 may be cast of any suitable metal and are preferably in the form of circular disks having eight flattened portions 5 formed on their peripheries for a purpose hereinafter to be described.

To connect the door wings with the disks, a plurality of straight grooves, one for each door wing, are formed on each face of the disks, and since in the present illustration, the revolving door is provided with four door wings, each face is provided with four grooves, the grooves on one face being indicated by the numerals 6, 7, 8 and 9, and the grooves on the other face being indicated by the numerals 6—A, 7—A, 8—A and 9—A. The grooves on each face are disposed tangentially, generally in the shape of a square, all of the grooves being spaced an equal distance from the center of the disk and each groove extending from the periphery of the disk to within a short distance of the next adjacent groove. Each groove is disposed at right angles to the next succeeding groove and the grooves on one face are disposed in the same vertical planes as the corresponding grooves on the other face of the disk. However, each of the grooves on the upper face is extended to the periphery of the disk at the opposite end to that groove on the lower face which is disposed in the same vertical plane. Thus, groove 6, as shown in Figure 3, is extended to the periphery of the disk at its right end, while groove 6—A on the lower face is extended to the periphery at the left. Because of this construction, the vertical plane of each of the grooves on the upper face will be intersected at right angles by the vertical plane of one of the grooves

on the lower face. Thus, in Figure 3, it will be seen that the vertical plane of the groove 6 on the upper face is intersected by the vertical plane of groove 9—A on the lower face, and this 5 is equally true of all of the grooves.

It will be understood, of course, that where only three door wings are used, it will only be necessary to provide three grooves on each face of the disk. The grooves will then be disposed 10 generally in the form of a triangle but will be formed substantially in the same manner as the grooves described above, each extending to the periphery of the disk at one end and being spaced an equal distance from the center.

15 Each of the door wings is provided with escutcheon plates 10, which are disposed on both faces and the inner edge of the door wing adjacent the point of connection with the wing supporting disks 3. The escutcheon plates and door wings are provided with slots or recesses 11 to permit of the entry of the disks and the escutcheon plates are extended through the slots so as to provide the plates 24 forming the upper and lower edges of the recesses. Projecting laterally 20 from either side of each door wing and integral with the escutcheon plate immediately above and below the recess 11, are the ears 12 and 13 respectively, to which are pivoted, as at 14 and 15, the guide shoes 16 and 17, the former being fitted 25 in the grooves formed in the upper surface of the disk, and the latter being fitted in the grooves formed in the lower surface of the disk. The guide shoes are preferably made of metal and are made to ride snugly in the grooves. In each 30 instance, the guide shoes 16 and 17 engage the grooves of the upper and lower faces of the disk respectively, whose vertical planes intersect at right angles. Since the shoes 16 engage the grooves in the upper face and the shoes 17 engage 35 the grooves in the lower face, it will be seen that each door wing will be firmly supported by the disks, and since the shoes are disposed in grooves, whose vertical planes intersect at right angles, each door wing will be permitted to move from a 40 normal radial position, as indicated in Figure 2, to a fully collapsed position, as shown in Figure 5. For example, when the wing 4, disposed in the upper right-hand portion of Figure 2, whose guide shoes ride in the grooves 9 and 8—A, swings to the 45 position shown in Figure 5, the shoe 17, riding in the lower groove 8—A, will slide in its groove toward the left, and the shoe 16 will slide downwardly in its groove 9 until the shoe 17 intersects the vertical plane of the groove 9. From that point 50 on the shoe 17 will continue sliding to the left in its groove 8—A, but the shoe 16 will then slide upwardly in its groove 9 until the door wings have assumed the position illustrated in Figure 5.

Slot 11, which permits of the entry of the disk 55 into the door wing, is extended into the body of the door wing beyond the point where the disk enters when the door wing is in normal radial position. This is to permit of the full collapsing of the door wings, at which time the disk necessarily 60 enters further into the body of the door wing. A closure 18, preferably formed of spring metal, is secured by means of the pressure screw 19 into the door wing so as to extend through that portion 65 of the recess 11 which is normally unoccupied by the disk. This closure may be flexed in either direction, but due to the fact that it is made out of spring metal, it will always return to its normal position, filling up the unoccupied portion of the recess when pressure upon it has been released. 70 Thus, when the doors are collapsed, as shown in

Figure 5, closures 18 of the door wings which have pivoted the greatest distance relative to the disk in collapsing, will be engaged by one of the flattened portions 5 of the disk and be flexed outwardly. It is for this purpose that the disk is provided with the flattened portions 5 so that when the closure 18 is flexed outwardly, its outer end will engage the flattened portion 5 and will fit smoothly and flatly against it without the projection which would necessarily result if the disk 10 was circular throughout its entire periphery.

To maintain the door wings in radial position during normal operation, the upper surface of the lower disk and the lower surface of the upper disk are provided with four small circular recesses 20, each disposed in the vertical plane of one of the door wings when in radial position. Each recess may be provided with a cylindrical lining 21 formed of a suitable metal and of a size to receive a latch member, such as the steel ball 22, held in a socket 23, which is secured in plate 24 immediately opposite recess 20 when the door wing is in radial position. The circumference of the lower end of the socket 23 is of such a size as to permit a portion of the ball to project and engage the recess 20. However, it is made small enough to prevent the ball from passing completely therethrough. Suitable mechanism to urge the ball 22 into engagement with the recess 20 is provided and it comprises a toggle joint composed of the link 25 pivoted at one end, by means of the pin 26, to the escutcheon plate 10 and pivoted at the other end, by the pin 28, to the link 27 which is provided with a socket 30 at its end for engaging the ball 22. A threaded shank 29 is also pivoted to the links by means of the pin 28, and screwed on the threads is a collar 30, which engages one end of a spiral spring 31. Thus the tension on the spring may be varied by shifting the position of the collar upon the screw threaded shank 29. The pressure of the spring 31 upon the toggle joint should be such as to press the ball 22 into recess 20, to hold the door wing in radial position under the usual pressure encountered in the operation of a revolving door. However, under abnormal pressure against opposing door wings, such as occurs during a panic, the spring must permit the ball 22 to withdraw from recess 20 so that the door wing may move out of radial position into collapsed 45 position.

Sometimes it is desired to collapse the wings of a revolving door during warm weather or to permit the entry of large objects. To facilitate the collapsing of the door wings under such conditions, manually controlled means are provided to relieve the tension upon the spring. For this reason the end of spring 31 preferably engages and is held in position by a recess 32 formed in a shiftable wedge block 33 which is provided with a beveled face 34 engaging the wedge 35. Opposing the beveled face 34 of the wedge block 33 is another shiftable wedge block 36 which is engaged by the opposite side of the wedge 35. The wedge blocks and the wedge are so formed that by shifting the wedge 35 downwardly, the wedge block 33 will shift away from the toggle joint, thereby relieving the tension of the spring 31 and in order to provide a simple and convenient means for simultaneously controlling the tension of both the upper and lower spring on each door wing, the upper and lower wedges 35 of each door wing are mounted upon rods 37 and 38 respectively. The lower end of rod 37 and the upper end of rod 38 are threaded and are 70 75

screwed into threaded openings formed in opposite ends of the slide piece 39 disposed in a recess formed in the door wing approximately midway between the top and bottom of the door (see Figs. 7, 8 and 9). The recess is covered by means of a plate 40 provided with a vertical slot or opening in its central portion in which a manually operated lever 41 is pivoted. The lever extends approximately from the point of pivot to the 10 end of the groove and the groove is preferably provided with enlarged end portions 43 so that the lever may be conveniently grasped between the fingers. The opposite end 44 of the lever is disposed at an angle to the handle portion so 15 that the lever resembles somewhat a bell crank, and this end engages an opening 45 formed in the face of the slide piece. When the lever 41 is swung to its uppermost position, the slide piece 39, the rods 38 and 31 and the upper and lower 20 wedges 35 will be shifted downwardly, thereby permitting the wedge blocks 33 to shift away from the toggle joint and relieve the tension of the springs 31. When the retaining mechanism is in this position, the door wings may readily 25 be swung to a fully collapsed position, as the spring will offer practically no resistance to the removal of the ball 22 from the recess 20. However, when the lever 41 is pivoted downwardly, as shown in Figures 7 and 9, the slide piece 39, 30 the rods 37 and 38, and consequently the wedges 35, will be shifted upwardly, causing the wedge blocks 33 to move toward the toggle joint and the tension of the springs 31 will accordingly be greatly increased. When the retaining mechanism 35 is in this position, the ball 22 will be strongly urged by the spring 31, acting upon the toggle joint, into engagement with the recess 20, and the door wings will remain in radial position under the pressure exerted during normal 40 operation and will only collapse when abnormal pressure is exerted in opposite directions upon opposing door wings, as occurs during a panic.

In addition to the above described manually controlled means for relieving the tension of the 45 spring 31, automatic means are provided whereby the tension on the spring is greatly increased when the wings are in normal radial position but is instantly relieved when the wings are moved into collapsed or partially collapsed position. 50 This means comprises a cylindrical projection 46 formed on the face of the wedge block 36 facing towards the spindle 1 and provided with a threaded opening in which is screwed the set screw 47. The cylindrical projection 46 and the 55 set screw 47 project from the inner end of the door wing through an opening formed in the end portion of the escutcheon plate facing the central spindle 1. The wedge block 36, block 33, and the wedge 35 are mounted so that they may 60 be shifted laterally, and it will be seen that the spring 31 will tend normally to urge the wedge block 33, the wedge 35, and accordingly, the wedge block 36 towards the inner end of the door wing. When the wings are out of normal radial 65 position, the projection 46 and set screw 47 can project outwardly beyond the inner end of the door wing, and the wedge block 36, wedge 35, and wedge block 33 will shift to the left thereby decreasing the tension of the spring 31 as shown 70 in Figure 5. When the doors are shifted to radial position, however, the end of the set screw 47 will engage the surface of the spindle 1 and will be forced inwardly, shifting the wedge block 36, the wedge 35, and the wedge block 33 toward 75 the right, as shown in Figure 7, thereby increas-

ing the tension upon the spring 31. It will thus be seen that when the greatest spring tension is needed, namely, when the wing is in normal radial position and the ball 22 is in engagement with the recess 20, the automatic mechanism just described will operate to increase the tension of the spring 31. When the wing is moved out of radial position the tension of the spring is decreased and the ball 22 will not be pressed against the face of the disk to obstruct the collapsing of the door. By varying the position of the set screw 47, the tension of the spring, while the wings are in radial position, may be adjusted. 10

The inner end of each door wing adjacent the central spindle 1 is preferably formed with a 15 vertically extending arcuate or V-shaped indentation 48 in its central portion in order to enable the door wing to fit in closer engagement with the central spindle and the inner ends of the escutcheon plates 40 are likewise provided 20 with arcuate indentations for the same purpose. However, the escutcheon plates are also provided with tapering projecting portions 49 extending from their central portion, which engage in similarly shaped openings 50 formed in 25 the surface of the central spindle. These projections are preferably formed on both the upper and lower escutcheon plates of each door wing and serve to hold the door wings more firmly when they are in their normal radial 30 position.

Thus, it will be seen that a revolving door has been provided in which the door wings are held firmly in position when in normal operation but which will permit of the full collapsing of the 35 door wings without any jamming when abnormal pressure is exerted upon opposing door wings. It will also be seen that effective retaining mechanism has been provided for releasably holding the door wings in radial position and 40 which has manual and automatic adjustments which will insure its positive operation.

Of course, it will be understood that many modifications may be made in the herein illustrated and described embodiment, such as 45 changing the number of door wings and the number of grooves provided in each of the disks, and such as altering the positions of the retaining mechanism and the adjusting means provided therefor.

What is claimed is:

1. In a collapsible revolving door structure, a rotatable spindle, a disk secured to said spindle and provided with a pair of straight grooves whose vertical planes intersect at right angles, 55 and a door wing provided with a pair of shoes engaging said grooves, said shoes being shiftable along said grooves in straight lines at right angles to each other and being pivotally secured to said door wing so that said door wing may 60 shift into and out of radial position with respect to said disk.

2. In a collapsible revolving door structure, a rotatable spindle, a disk secured to said spindle and provided on opposite faces with a pair of 65 straight grooves whose vertical planes intersect at right angles, a door wing, and a pair of shoes on said door wing and engaging said grooves, said shoes being shiftable along said grooves in straight lines at right angles to each other and 70 being pivotally secured to said door wing so that said door wing may shift into and out of radial position with respect to said disk.

3. In a collapsible revolving door structure, a rotatable spindle, a disk secured to said spindle, 75

- a door wing, and a pair of pivotal connections between said disk and door wing, said connections being shiftable in straight lines at right angles to each other.
5. The combination with a collapsible revolving door structure having a rotatable spindle, a disk secured to said spindle, a recess formed in said disk, a door wing having pivotal connection with said disk, and a shiftable member mounted 10 on said door wing and engageable in said recess to releasably hold the door wing in radial position of a spring-pressed toggle joint mounted in said door wing and engageable with said shiftable member for urging it into engagement 15 with said recess.
5. In a collapsible revolving door structure, a rotatable spindle, a disk secured to said spindle, a recess formed in said disk, a door wing having pivotal connection with said disk, a member 20 mounted on said door wing and engageable in said recess to releasably hold the door wing in radial position, means including a spring for urging said member into engagement with said recess, and means including a shiftable spring 25 mounting and a member projecting beyond the inner end of said door wing and cooperable with the central spindle to vary the tension of said spring as the wing moves into and out of radial position.
30. 6. In a collapsible revolving door structure, a rotatable spindle, a disk secured to said spindle, a circular recess formed in said disk, a door wing provided with a socket and having pivotal connection with said disk, a ball held in said socket and engageable in said recess, means including a toggle joint and a spring for urging said ball into engagement with said recess, a shiftable mounting for said spring, and means including a member projecting beyond the inner end of said 35 door wing and engageable with said spindle for shifting the position of said spring mounting as the door moves into and out of radial position.
7. In a collapsible revolving door structure, a rotatable spindle, a pair of disks, each provided 45 with a circular recess, a door wing mounted on said disks for pivotal movement, shiftable members mounted on said door wing and engageable with said recesses to hold the wing in radial position, a pair of springs for urging said members 50 into engagement with the recesses, and manually operated means for simultaneously controlling the tension of both of said springs.
8. In a collapsible revolving door structure, a rotatable spindle, a pair of disks each provided 55 with a recess, a door wing mounted on said disks for pivotal movement, shiftable members mounted on said door wing and engageable with said recesses to hold the wing in radial position, a pair of springs for urging said members into engagement with the recesses, and manually operated means including shiftable spring mountings for each of said springs and a lever for shifting said mountings for simultaneously controlling the tension of both of said springs.
65. 9. In a collapsible revolving door structure, a rotatable spindle, a pair of disks each provided with a recess, a door wing mounted on said disks for pivotal movement, shiftable members mounted on said door wing and engageable with 70 said recesses to hold the wing in radial position, a pair of springs for urging said members into engagement with the recesses, manually operated means for simultaneously controlling the tension of both of said springs, and automatically operable means for varying the tension of
- said springs as the door wing moves into and out of radial position.
10. In a collapsible revolving door structure, a rotatable spindle, a disk secured to said spindle, a door wing connected to said disk for pivotal movement, and means for releasably holding said door wing in radial position, said means comprising a ball-and-socket connection between said disk and door wing and a tapering projection on the inner end of said door wing engageable in a 10 similarly shaped opening formed in the spindle. 5
11. In a collapsible revolving door structure, a rotatable spindle, a pair of disks secured to said spindle and each provided with a pair of straight grooves whose vertical planes intersect at right angles, a door wing, four guide shoes pivoted to said door wing and engaging said grooves, a circular recess formed in each disk, shiftable members mounted on said door wing and engageable in said recesses, means including a pair of springs 20 for urging said members into engagement with said recesses, means for manually controlling the tension of both of said springs simultaneously, and means for automatically varying the tension of said springs as the door wing moves into and 25 out of radial position.
12. In a collapsible revolving door structure, a rotatable spindle, a disk secured to said spindle, a door wing connected to said disk for pivotal movement and provided with a slot engaging said disk, 30 said disk extending into said slot for a portion only of the depth of the slot when the door wing is in radial position, and a flexible closure secured to said door wing and extending through the remaining portion of the slot. 35
13. In a collapsible revolving door structure, a rotatable spindle, a door wing provided with a slot, a flexible closure secured to said door wing and extending through a portion of said slot, a disk secured to said spindle and extending into 40 said slot, and a pivotal connection between said door wing and disk so that the door wing is shiftable from a radial to a collapsed position, said closure extending to the periphery of the disk when the door wing is in radial position and said disk being provided with a flattened portion in its periphery against which the closure rests when the door wing is in collapsed position.
14. In a collapsible revolving door structure, a rotatable spindle, a disk secured to and rotatable 50 with said spindle, a door wing connected to said disk for pivotal movement, and means including a circular recess in said disk and a ball and a spring-pressed toggle joint in said door wing for releasably holding said wing in radial position. 55
15. In a collapsible revolving door structure, a rotatable spindle, a pair of disks mounted on said spindle each provided with a recess, a door wing mounted on said disks for pivotal movement, a pair of shiftable members carried by said door 60 wing each engageable with one of said recesses to hold the wing in radial position, a pair of springs for urging said shiftable members into engagement with said recesses, adjustable means disposed inside said door wing for independently 65 adjusting the tension of each of said springs, and means including an exposed manipulator for simultaneously releasing the tension of both of said springs.
16. In a collapsible revolving door, means for 70 releasably locking a door wing in radial position with respect to a disc mounted on the central spindle of the door comprising a recess formed in said disc, a detent mounted in the door wing and engageable with said recess, a toggle engaging 75

said detent and a spring engaging said toggle to urge said detent into engagement with the recess.

17. In a collapsible revolving door, means for 5 releasably locking a door wing in radial position with respect to a disc mounted on the central spindle of the door comprising a recess formed in said disc, a detent mounted in the door wing and engageable with said recess, a toggle engaging 10 said detent, a spring engaging said toggle to urge said detent into engagement with the recess, means disposed inside said door wing for adjusting the tension of said spring and means including a manipulator exposed on an outer face of the 15 door wing for releasing the tension of said spring.

18. The combination with a collapsible revolving door of the type comprising a rotatable central spindle, a disc mounted on said spindle and a door wing secured to said disc for pivotal movement, of means for releasably holding said door wing in radial position, including a recess formed 5 in one face of the disc, a detent carried by the door wing and engageable with said recess, a double link toggle having one link pivoted to the door wing and the other link pivoted to the first link and engaging said detent and a spring engaging 10 said links at the point of connection so as to urge said detent into engagement with said recess.

BURNS H. UHRICH. 15
